UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-LIGHT.

SPECIFICATION forming part of Design No. 27,983, dated December 7, 1897.

Application filed October 21, 1897. Serial No. 655,974. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Lights, of which the following is a description.

My invention relates to designs for prism-lights.

10 Figure 1 is a plan view of a prism-light embodying my design. Fig. 2 is a cross-section therethrough.

A is the body of the prism-light.

15 B are ornamental lines formed in the surface of the body on one side; C C, prisms on the other side; D D, open spaces.

The essential features of my design are found in a prism-light comprising a substantially flat and comparatively thin body with 20 prisms on one side and on the other an ornamental pattern produced on the body of the prism-light and formed in a rectangular figure intermediate between the center and the outer edge of the surface.

I claim—

25 A design for a prism-light, substantially as shown and described.

FRANK L. WRIGHT.
